UNITED STATES PATENT OFFICE

168,451

TOY BALLOON

William Anthony Ingram, Lea Bridge, London,
England

Application February 29, 1952, Serial No. 18,726
In Great Britain January 28, 1952

Term of patent 3½ years

(Cl. D34—15)

To all whom it may concern:

Be it known that I, William Anthony Ingram, a subject of the Queen of Great Britain, residing at Lea Bridge, London, E. 5, England, have invented a new, original, and ornamental Design for a Toy Balloon, of which the following is a specification, reference being had to the accompanying drawing, forming a part hereof.

Figure 1 is a front elevational view of a toy balloon, showing my new design, and

Figure 2 is a side view.

I claim:

The ornamental design for a toy balloon, as shown.

WILLIAM ANTHONY INGRAM.
